UNITED STATES PATENT OFFICE.

OSCAR F. LINDBERG, OF BRADFORD, PENNSYLVANIA.

CHAPLET.

1,089,001.

Specification of Letters Patent.

Patented Mar. 3, 1914.

Application filed May 22, 1913. Serial No. 769,315.

To all whom it may concern:

Be it known that I, OSCAR F. LINDBERG, a citizen of the United States, residing at Bradford, in the county of McKean and State of Pennsylvania, have invented certain new and useful Improvements in Chaplets, of which the following is a specification.

This invention relates to chaplets, and 10 has for its object the provision of a simple and inexpensive device which may be placed within a mold and readily adjusted to the distance or space between the core and the adjacent walls of the mold.

15 A secondary object of the invention is to provide a chaplet of such form that it may readily unite with the casting in the event that the molten metal should not be hot enough to entirely melt the chaplet.

20 Other incidental objects of the invention will appear as the description of the same proceeds, and the invention resides in certain novel features which will be particularly pointed out in the claims following 25 the description.

The invention is fully illustrated in the accompanying drawings, in which:

Figure 1 is a section of a mold showing my improved chaplet in position thereon; Fig. 30 2 is a perspective view of the chaplet showing the members of the same separated but in their proper relative positions; Figs. 3 and 4 are end views of the device showing different adjustments of the same; Fig. 5 is 35 a plan view of the lower member; and Fig. 6 is a side elevation of the chaplet.

In carrying out my invention, I employ 40 an upper member 1 and a lower member 2, each of which is preferably constructed of sheet metal and comprises a base plate and a standard projecting from the base plate. In the upper member 1 the base plate 3 constitutes the top of the chaplet and the standard 4 projecting therefrom is constructed 45 with parallel spaced arms 5 and 6 which are preferably of unequal length and extend from the plate 3 at the center thereof, the ends of the members of the standard being connected by a cross head 7 which is preferably provided with lips or tongues 8 adapted to extend through small slots in the plate 3 and be bent over into depressions in the outer face of said base plate so as to hold the standard to the plate. The lower member 50 2 of the chaplet comprises a base plate 9 and a standard 10 extending the full

length of the plate along the medial longitudinal line thereof and this standard, as shown most clearly in Figs. 2 and 5, is provided in its opposite faces with vertical 60 grooves 11 adapted to receive the longer member 6 of the standard 4 of the top member. The distance between the members 5 and 6 of the standard 4 should be approximately equal to the thickness of the 65 standard 10 so that when the members 5 and 6 are engaged over the standard 10 the parts will be firmly held together, and, inasmuch as the longer arm 6 of the standard 4 will have a prolonged bearing between the 70 vertical walls of the groove 11 engaged thereby, twisting of the upper member relative to the lower member will be prevented. By reference to Fig. 6, it will be noted that the standard 10 is not of uniform height 75 throughout its length but has a different height at each groove 11 and it will, therefore, be readily understood that the device may be readily adjusted to support the core 80 at the proper height within the mold by engaging the standard 4 of the upper member in one or another groove 11 of the lower member. The standard 10 is preferably formed with tongues or lips 12 upon its lower edge which are adapted to extend 85 through small slots in the base plate 9 and be bent over into depressions in the outer face of the said plate so as to hold the standard in proper position relative to the base plate. 90

It is thought the advantages of my improved device will be readily appreciated from the foregoing description, taken in connection with the accompanying drawings.

Heretofore it has been necessary to provide 95 a great variety of chaplets of different heights so that one or another chaplet might be used according to the requirements of any particular mold. By the use of my device a single chaplet is adapted for use in a 100 large variety of molds so that time heretofore lost in determining just which chaplet should be used will be now saved. A firm support for the core is provided by my chaplet and the two members may be easily 105 and quickly fitted together so that the mold may be rapidly prepared for the casting. Should the molten metal, after it is poured, cool too rapidly to entirely melt the chaplet, it will enter the grooves 11 and thereby form 110 a good strong tie, so that weakness in the casting will be overcome. The device is ob-

viously simple and inexpensive and in practice will be found highly efficient.

The terms "upper" and "lower" employed herein are employed for convenience of reference and are not to be construed as limitations.

What I claim is:—

1. A chaplet comprising a lower member having a standard provided with grooves of unequal lengths, and an upper member having a standard adapted to engage in one of said grooves.

2. A chaplet comprising a lower plate, a standard rising therefrom and provided with vertical grooves in its opposite faces, the various heights of the standard in the planes of the respective grooves being unequal, and an upper plate having means for engaging one of said grooves.

20 3. A chaplet comprising a lower member having grooved supports of unequal height

rising therefrom, and an upper member having a depending standard adapted to engage one of said supports.

4. A chaplet comprising a lower plate, 25 a grooved support rising therefrom, an upper plate having a pair of parallel members depending therefrom and adapted to fit over said grooved support and engage the groove therein, and a connection between said members to rest upon said support.

5. A chaplet comprising a lower member, a support therefor and having a stepped upper edge, and an upper member constructed to fit over said support and rest 35 upon a step in the upper edge thereof.

In testimony whereof I affix my signature in presence of two witnesses.

OSCAR F. LINDBERG. [L. S.]
